[57] CLAIM

The ornamental design for a hair roller or similar article, as shown and described.

DESCRIPTION

FIG. 1 is a front elevational view of a hair roller showing our new design;

FIG. 2 is a side elevational view thereof. The side opposite is a mirror image of the side shown;

FIG. 3 is a rear elevational view thereof;

FIG. 4 is a top plan view thereof;

FIG. 5 is a bottom plan view thereof;

FIG. 6 is a cross-sectional view, taken on the line 6—6 of FIG. 1;

FIG. 7 is a front elevational view of a second modified embodiment;

FIG. 8 is a side elevational view thereof. The side opposite is a mirror image of the side shown;

FIG. 9 is a rear elevational view thereof;

FIG. 10 is a top plan view thereof;

FIG. 11 is a bottom plan view thereof;

FIG. 12 is a cross-sectional view, taken on the line 12—12 of FIG. 7;

FIG. 13 is a front elevational view of a third modified embodiment;

FIG. 14 is a side elevational view thereof. The side opposite is a mirror image of the side shown;

FIG. 15 is a rear elevational view thereof;

FIG. 16 is a top plan view thereof;

FIG. 17 is a bottom plan view thereof; and

FIG. 18 is a cross sectional view taken on the line 18—18 of FIG. 13.
